ABSTRACT OF THE DISCLOSURE

Disclosed herein are stable two-phase liquid detergent emulsions that maintain stability without the use of additional stabilizing agents. These autostabilized emulsions are made up of anionic, zwitterionic or simipolar compounds, electrolytes, alcohols and water. Autostabilized emulsions are capable of supporting water-insoluble particulate material.

This is a continuation of application Ser. No. 888,862, filed Dec. 29, 1969, and now abandoned.

BACKGROUND OF THE INVENTION

There is an ever increasing demand for liquid detergent compositions that are useful as, e.g., liquid scouring cleanser compositions or as liquid abrasive cleaner compositions. These liquid detergent cleaning compositions are provided in a convenient form. The compositions of this invention are especially formulated for the above expressed cleaning applications.

To obtain optimum cleaning ability and wide consumer acceptance, detergent compositions of this invention must be homogeneous and easily pourable. The above compositions should maintain their homogeneity during ordinary periods of storage and use. It is highly desirable that the formulation of the invention exhibits Bingham plastic characteristics, i.e., exhibit a substantial yield value to keep the particulate materials suspended.

This invention relates to the formulation of stable two-phase liquid detergent emulsions, called autostabilized emulsions, capable of supporting water-insoluble particulates which have utility as, e.g., hard surface cleaners. Autostabilized emulsions can be formed without the use of additional stabilizing agents. Due to the addition of alcohol, the autostabilized emulsions can support higher electrolyte levels than previously known two-phase emulsion compositions, making the autostabilized emulsions much more desirable as, e.g., hard surface cleaners.

SUMMARY OF THE INVENTION

The formulations of this invention, having the above-described utility, are novel, stable two-phase liquid detergent emulsions, referred to as autostabilized emulsions.

An object of this invention is to formulate autostabilized two-phase liquid detergent emulsions, i.e., emulsions that are stabilized without the use of hydrotropes or other stabilizing agents, capable of supporting water-insoluble particulates.

A further object of this invention is to formulate autostabilized emulsions that are useful, e.g., in liquid scouring cleanser compositions or as liquid abrasive cleaner compositions.

THE PRIOR ART

Many of the components used in the present invention are well known in combination in the detergent art on two-phase liquid detergent emulsions. This is pointed out in U.S. Pats. 2,999,068, 3,232,878 and 3,281,267.

In U.S. Pats. 3,272,753, 3,332,875, 3,179,599, 3,035,982 and 3,179,598, the use of ethanol in various liquid detergent compositions is disclosed. Ethanol, as used in

2

the art, is a solvent that allows the combination of components in a more stable solution. The art does not suggest that as an additive ethanol allows an increase in electrolyte content of an already stable two-phase emulsion as in the present invention. Thus, although the art teaches some stable two-phase emulsions with various components that are similar to those used in the present invention, the art fails to teach the present invention which contains very specific components and composition ranges and which provides for autostabilized two-phase emulsions capable of supporting water-insoluble particulate material and unexpectedly large additions of electrolyte for use in, e.g., liquid scouring cleanser compositions and liquid abrasive cleaner compositions.

DETAILED DESCRIPTION OF THE INVENTION

The liquid detergent compositions of this invention are autostabilized, two-phase, liquid detergent emulsions capable of supporting water-insoluble particulate material, said autostabilized emulsions consisting essentially of:

- (1) from about 4% to about 28% by weight of:
(a) an anionic synthetic detergent surfactant having the general formula

or

wherein R_1 and R_2 are straight chain alkyl radicals containing from about 10 to about 16 carbon atoms and M is a cation selected from the group consisting of potassium, sodium, ammonium, monoethanolammonium, diethanolammonium, and triethanolammonium cations; and

- (b) a zwitterionic quaternary ammonium synthetic detergent surfactant having the general formula

wherein R_3 is an alkyl radical containing from about 10 to about 16 carbon atoms, and R_4 is selected from the group consisting of hydrogen and hydroxyl; or

- (c) a simipolar surfactant having the general formula

wherein R_5 is an alkyl radical containing from about 10 to 16 carbon atoms;

- (2) from 10% to about 20% by weight of a polyvalent electrolyte selected from the group consisting of tetrapotassium pyrophosphate, nitrilotriacetate, and ethane-1-hydroxy-1,1-diphosphonate;
(3) from about 2% to about 9% of a lower alcohol containing from 1 to about 5 carbon atoms;
(4) the balance water;

wherein the ratio of zwitterionic or simipolar to anionic surfactants is from about 2:1 to about 1:3.

The individual components of the autostabilized emulsions of this invention are anionic detergent, simipolar detergent or zwitterionic synthetic detergent, electrolyte, alcohol and water. Optional components include minor

ingredients which have aesthetic value or which improve the effectiveness of the autostabilized emulsions. As a preferred embodiment, insoluble particulate material can be added to the autostabilized emulsions of this invention, since all of the autostabilized emulsions of this invention are capable of suspending insoluble particulate materials.

In the autostabilized emulsions of this emulsion, it has been discovered that the surfactants must be a mixture of a semipolar or zwitterionic surfactant with an anionic surfactant in specific proportions, i.e., a ratio of about 2:1 to about 1:3 respectively and in a specific amount, i.e., from about 4% to about 28% by weight of the autostabilized emulsion compositions. Anionic surfactants and zwitterionic or semipolar surfactants, when used separately, will not provide a stable support for insoluble particulate materials. However, when they are used together as specified below, they unexpectedly cooperate to provide a stable medium with a yield value that will support insoluble particulate material.

The total amount of zwitterionic or semipolar and anionic surfactants, i.e., from about 4% to about 28% by weight of the composition, and the relative amount in which the above surfactants are present in the autostabilized emulsion compositions of this invention, i.e., a ratio of zwitterionic or semipolar to anionic surfactant of about 2:1 to about 1:3, is more important in the practice of this invention than the exact amount of each surfactant in the autostabilized emulsions.

While the exact amount of each detergent surfactant is of little significance, the total amount of the surfactants is important. The total amount of surfactant used in an autostabilized emulsion determines the yield value and the ability to dissolve grease and dirt. If there is an excessive amount of total surfactant present in the autostabilized emulsion, i.e., above about 28% by weight of the composition, the autostabilized emulsion becomes too thick and unmanageable.

The relative amount of zwitterionic or semipolar to anionic detergent surfactants, i.e., a weight ratio of zwitterionic or semipolar to anionic surfactant, sharply affects the ability of the auto stabilized emulsion to support insoluble particulate material. When the ratio of zwitterionic or semipolar to anionic surfactant falls within the proper relative amount, i.e., a ratio of about 2:1 to about 1:3, the autostabilized emulsions of this invention have excellent yield values, and they maintain phase stability. It is preferred that the ratio of zwitterionic or semipolar to anionic surfactant be about 1:1. The exact value of this ratio depends on other materials present in the autostabilized emulsions.

It has been discovered that only certain members of each class are functional. Two anionic detergents provide the necessary emulsion stability; these detergents are alkyl glyceryl ether sulfonate and alkylbenzene sulfonate. Two zwitterionic synthetic detergents provide the necessary emulsion stability; these detergents are hydroxy ammonio propane sulfonate and ammonio propane sulfonate. One semipolar detergent alternatively provides the necessary emulsion stability; this is alkyldimethylamine oxide. The semipolar detergent, i.e., alkyldimethylamine oxide is more preferred over the zwitterionic detergents in combination with the other components of the autostabilized emulsions of this invention.

From about 10% to about 20% of the finished composition is polyvalent electrolyte or builder. Only the addition of a lower alcohol containing 1 to about 5 carbon atoms, preferably ethanol, in an amount from about 2% to about 9%, preferably about 5%, allows this relatively high amount of electrolyte to be used with no effect on stability. The preferred amount of electrolyte as used in the compositions of this invention is about 15% by weight of the composition. This increase in electrolyte content assists in maximizing stability and increasing the cleaning characteristics of the autostabilized emulsion. Various electrolytes can be used, e.g., tetrapotassium

pyrophosphate, nitrolotriacetate and ethane-1-hydroxy-1,1-diphosphonate.

Tetrapotassium pyrophosphate is preferred to other electrolytes because of its good cleaning characteristics and excellent solubility characteristics. The liquid detergent compositions built with tetrapotassium pyrophosphate also exhibit excellent stability characteristics over a wide range of temperatures.

Although other electrolytes may be used, their operating region in which phase stability is maintained is relatively small. The operating region varies for each specific combination of components. The addition of lower alcohols by expanding the operating region of autostabilized emulsions allows the addition of higher levels of electrolyte without the normally resulting instability that occurs if higher amounts of builder are added without the lower alcohol. In previous compositions, only from 1% to 10% electrolyte could be used if stability was to be maintained. In this invention, with lower alcohol addition, 10% to 20% is used making autostabilized emulsions more effective as, e.g., hard surface cleaners. An operating region in the range wherein the different components in the autostabilized emulsion can be used in various amounts and phase stability is still maintained.

25 The balance of the composition is water. It is preferred that from about 30% to about 50% by weight of the finished composition be water when the insoluble particulate material is added to the autostabilized emulsions to optimize yield values and cleaning characteristics of the finished product. The pH of the compositions is in the range from about 7 to about 12, preferably from about 9 to about 11.

30 In the practice of this invention, from 5% to about 75% of the composition can be insoluble particulate material. It is preferred, however, that from about 40% to about 50% by weight of the finished composition be insoluble particulate material.

35 Within the preferred range of insoluble particulate material (about 40% to about 50%), it is preferred that about 4% to about 20% of the supporting medium be detergent surfactants. At higher than the specified detergent concentrations, the combined detergent and insoluble particulate materials make the compositions too thick to be manageable; at lower than the specified detergent concentrations there is not enough detergent to provide sufficient yield value to support the insoluble particulate material. The upper limit on combined detergent and insoluble particulate material is a functional one, and is best expressed in terms of apparent viscosity. The detergent compositions of the preferred embodiment of this invention must have apparent viscosity below about 12,000 centipoises. It is preferred that the apparent viscosity be below about 10,000 centipoises. As used herein and elsewhere in this specification, "apparent viscosity" means the value obtained with a Brookfield viscometer, Model LVF, using spindle number 3 at 12 r.p.m. At lower (below 40%) insoluble particulate material concentrations, the concentration of total detergent in the supporting medium becomes less important.

40 45 50 55 60 65 70 75 The insoluble, particulate material which can be utilized in this invention can comprise abrasives, bactericides, or other insoluble particulate material having a particle size diameter ranging from about 1 to about 200 microns and a density of from about 0.5 to about 5.0. It is preferred that the diameter of the particles range from about 2 microns to about 60 microns and that the density range from about 1.0 to about 2.8. The insoluble particulate materials which can be utilized in this invention include, but are not limited to, quartz, pumice, pumicite, talc, silica, sand, calcium carbonate, china clay, zirconium silicate, bentonite, diatomaceous earth, whiting, feldspar, and aluminum oxide. Silica is the preferred insoluble particulate material for use herein.

75 Minor amounts of materials which make the composition of this invention more attractive or more effective

can be added, e.g., soluble sodium carboxymethylcellulose, tarnish inhibitors such as benzotriazole or ethylene-thiourea, brighteners, bleaches, fluorescers, dyes, bluing agents, perfumes, bactericides and corrosion inhibitors, if they do not significantly alter the excellent physical properties of this composition.

In Bingham plastics, insoluble particulate material is suspended because the stress imposed by the particles does not exceed the yield value of the liquid. Of course, if the yield value of the supporting medium should decrease sufficiently for any reason, the particles would no longer be suspended. This could be caused, for example,

it contains upwards of 75% of the total electrolyte. Neat is poorly conductive, more or less 3,000 μ mhos/cm. The stable emulsions have conductivities less than 25,000 μ mhos/cm. instead of the greater than 80,000 μ mhos/cm. expected for a lye continuous emulsion. (μ Mhos/cm. means micro ohms per centimeter, which is a unit of conductivity.)

The following example is given additionally to illustrate the nature of the invention and it will be understood that the invention is not limited thereto. In this example, as in the specification, and claims, proportions indicated are percent by weight unless otherwise specified.

EXAMPLE I

Sample	Total sur- factant	Percent					Phases
		Coconut alkyl- dimethyl- amine oxide	Linear coconut alkyl- benzene sulfonate	Tetrapo- tassium pyrophos- phate	Etha- nol	H ₂ O	
		Neat/Niger/Lye					
1.....	5	3.06	1.94	10	5	Balance.	X
2.....	5	3.06	1.94	15	5	do.....	X
3.....	5	3.06	1.94	20	5	do.....	X
4.....	10	6.12	3.88	10	5	do.....	X
5.....	10	6.12	3.88	15	5	do.....	X
6.....	10	6.12	3.88	20	5	do.....	X

by a physical or chemical change in the supporting medium, e.g., if the autostabilized emulsion settles into layers upon standing, the yield value can be lost temporarily. The original composition with its yield value can be reconstituted by mixing. If a chemical reaction either consumes a vital component or produces a damaging one, the loss of yield value can be permanent.

Hydrotropes such as sodium or potassium xylene-sulfonate, toluenesulfonate, or benzenesulfonate, should not be present in these compositions. Even very small amounts of these hydrotropes solubilize the discrete phase into the continuous phase. Thus, the detergent composition can become a one-phase solution and loses its Bingham plastic characteristics with resultant settling of the insoluble particulate material. The composition, in this condition, is aesthetically undesirable and not salable on the retail consumer market or the industrial market.

Also to be avoided are soaps, amides, and other materials which are presently or potentially solubilizing agents, or which combine with water hardness ions.

The compositions of this invention are formulated by mixing the components together in the amounts desired. The order of mixing does not affect the stability of the emulsion. Any of the desired optional ingredients can then be added.

Ultracentrifuging is used in the following example to completely separate the phases in the autostabilized emulsions and to determine the relative proportions of the phases present. The autostabilized emulsions all contained a neat phase and a lye phase. The autostabilized emulsions are believed to be lye in neat emulsions with the lye phase being the dispersed phase. This is unexpected since the lye phase is generally more or less 75% of the total composition by volume. Evidence for this theory is twofold. (1) The relatively poor dispersibility of these autostabilized emulsions is expected if neat phase is continuous since the neat phase would have to go through middle phase in the process of dissolving. If the lye phase is continuous the emulsions disperse very well in water. However, it is discovered that, in fact, autostabilized emulsions have poor dispersibility. Dispersibility improves, however, as the amount of surfactant is lessened in the autostabilized emulsions. Thus, in the practice of this invention, it has been discovered that emulsions maximize their dispersibility and cleaning characteristics by the use of the particular components and particular proportions of each component in the autostabilized emulsions disclosed. (2) Conductivity measurements gave further evidence that the stable emulsions are lye in neat rather than neat in lye. Lye is very conductive greater than 100,000 μ mhos/cm. as expected since

The example shows various formulations of this invention by demonstrating that stable neat-lye formulations remain stable with increased electrolyte addition of up to about 20% where ethanol is added, e.g., sample number 3, shows a neat-lye emulsion with an electrolyte content of 20% by weight of the composition. These formulations were found to have excellent cleaning characteristics and the ability to support water-insoluble particulates that makes them useful as, e.g., hard surface cleaners. More specifically, silica is added to each of the compositions of the above example in an amount of 45% by weight of the compositions. The compositions of the above example remain autostabilized emulsions and support the silica.

What is claimed is:

1. An autostabilized, two-phase hydrotrope- and soap-free liquid abrasive detergent emulsion containing a mixture of surfactants in a proportion that cooperatively provides a stable medium having a yield value capable of supporting insoluble particulate material, said autostabilized emulsions consisting essentially of

(a) from about 4% to about 28% by weight of a mixture of

(i) a linear alkyl benzene sulphonate having the general formula

in which R_1 is a straight chain alkyl radical containing from about 10 to 16 carbon atoms and M is a cation selected from the group consisting of potassium, sodium, ammonium, monoethanolammonium, diethanolammonium and triethanolammonium cations and

(ii) a semipolar surfactant having the general formula

wherein R_5 is an alkyl radical containing from about 10 to 16 carbon atoms;

(b) from 10% to about 20% by weight of a polyvalent electrolyte selected from the group consisting of tetrapotassium pyrophosphate, nitrilotriacetate and ethane-1-hydroxy-1,1-diphosphonate;

(c) from about 2% to about 9% of a lower alcohol containing from 1 to about 5 carbon atoms;

(d) from about 5% to about 75% by weight of an abrasive insoluble particulate material having a

particle size diameter ranging from about 1 to about 200 microns and a density of from about 0.5 to about 5; and
 5
 (e) the balance being water;
 wherein the ratio by weight of the amine oxide to the alkyl benzene sulphonate is from about 1.6:1 to about 1:1.

2. An autostabilized, two-phase hydrotrope- and soap-free liquid abrasive detergent emulsion containing a mixture of surfactants in a proportion that cooperatively provides a stable medium having a yield value capable of supporting insoluble particulate material, said autostabilized emulsions consisting essentially of

- (a) from about 5% to about 10% by weight of a mixture of sodium coconut linear alkyl benzene sulphonate and coconut alkyl dimethyl amine oxide, wherein the ratio by weight of said amine oxide to said alkyl benzene sulphonate is in the range of about 1.6:1 to about 1.5:1;
- (b) from about 10% to about 20% by weight of a polyvalent electrolyte selected from the group consisting of tetrapotassium pyrophosphate, nitrilotriacetate and ethane-1-hydroxy-1,1-diphosphonate;
- (c) from about 2% to about 9% of a lower alcohol containing from 1 to about 5 carbon atoms;

- (d) about 45% by weight of silica having a particle size diameter ranging from about 1 to about 200 microns and a density of from about 0.5 to about 5;
- (e) the balance being water.
